US0D1026417S

(12) **United States Design Patent** (10) Patent No.: **US D1,026,417 S**
(45) Date of Patent: ** May 14, 2024

(54) **BOOT**

(71) Applicant: **ROTHY'S, INC.**, San Francisco, CA (US)

(72) Inventors: **La Vion Gibson**, San Francisco, CA (US); **William Roth Martin**, San Francisco, CA (US); **Matthew Taylor**, London (GB)

(73) Assignee: **ROTHY'S, INC.**, San Francisco, CA (US)

(**) Term: **15 Years**

(21) Appl. No.: **29/809,251**

(22) Filed: **Sep. 27, 2021**

(51) LOC (14) Cl. **02-04**

(52) U.S. Cl.

USPC **D2/909**; D2/970

(57) **CLAIM**

The ornamental design for a boot, as shown and described.

DESCRIPTION

FIG. 1 is front right perspective view of a boot showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in FIGS. 1-7 are included for the purpose of illustrating environmental structure of the boot and form no part of the claimed design.

1 Claim, 7 Drawing Sheets
